US0D1076074S

(12) **United States Design Patent** (10) Patent No.: **US D1,076,074 S**
(45) Date of Patent: ** May 20, 2025

(54) **BOND PATTERN FOR SUBSTRATE**

(71) Applicant: **The Procter & Gamble Company**,
Cincinnati, OH (US)

(72) Inventors: **Ray Dennis Dria**, Mason, OH (US);
Michael Joseph Page, Cincinnati, OH (US);
Joseph Leslie Grolmes, Madeira,
OH (US); **Scott Alan King**, Liberty
Township, OH (US); **Matthew Steven
Ritter**, Liberty Township, OH (US);
Christopher Colin Arp, Mason, OH
(US)

(73) Assignee: **The Procter & Gamble Company**,
Cincinnati, OH (US)

(**) Term: **15 Years**

(21) Appl. No.: **29/938,093**

(22) Filed: **Apr. 18, 2024**

(57) **CLAIM**

The ornamental design for the bond pattern for a substrate,
as shown and described.

DESCRIPTION

FIG. 1 is a perspective view of a bond pattern for a substrate;
FIG. 2 is a view of the front side of the bond pattern for a
substrate of FIG. 1;
FIG. 3 is a view of the right side of the bond pattern for a
substrate of FIG. 1;
FIG. 4 is a view of the back side of the bond pattern for a
substrate of FIG. 1;
FIG. 5 is a view of the left side of the bond pattern for a
substrate of FIG. 1;
FIG. 6 is a view of the top side of the bond pattern for a
substrate of FIG. 1; and,
FIG. 7 is a view of the bottom side of the bond pattern for
a substrate of FIG. 1.
The broken lines are included for the purpose of illustrating
environment and form no part of the claimed design.

1 Claim, 4 Drawing Sheets

Related U.S. Application Data

division of application No. 29/807,499, filed on Sep. 13, 2021, now Pat. No. Des. 973,200, which is a continuation of application No. 16/357,685, filed on Mar. 19, 2019, now Pat. No. 11,642,255.
